(57) CLAIM

The ornamental design for a cosmetic makeup sponge/blender container, as shown and described.

DESCRIPTION

FIG. 1 is a frontal perspective view of a cosmetic makeup sponge/blender container shown in a closed condition in accordance with a first embodiment of the invention;

FIG. 2 is a front view of the cosmetic makeup sponge/blender container of FIG. 1;

FIG. 3 is a rear view of the cosmetic makeup sponge/blender container of FIG. 1;

FIG. 4 is a first side view of the cosmetic makeup sponge/blender container of FIG. 1;

FIG. 5 is a second side view of the cosmetic makeup sponge/blender container of FIG. 1;

FIG. 6 is a top view of the cosmetic makeup sponge/blender container of FIG. 1;

FIG. 7 is a bottom view of the cosmetic makeup sponge/blender container of FIG. 1;

FIG. 8 is a frontal perspective view of a cosmetic makeup sponge/blender container shown in a closed condition in accordance with a second embodiment of the invention;

FIG. 9 is a front view of the cosmetic makeup sponge/blender container of FIG. 8;

FIG. 10 is a rear view of the cosmetic makeup sponge/blender container of FIG. 8;

FIG. 11 is a first side view of the cosmetic makeup sponge/blender container of FIG. 8;

FIG. 12 is a second side view of the cosmetic makeup sponge/blender container of FIG. 8;

FIG. 13 is a top view of the cosmetic makeup sponge/blender container of FIG. 8; and,

FIG. 14 is a bottom view of the cosmetic makeup sponge/blender container of FIG. 8.

The broken lines shown in the drawings illustrate portions of the cosmetic makeup sponge/blender container and form no part of the claimed design.

1 Claim, 14 Drawing Sheets
